The ornamental design for a combined container and cap, as shown and described.

DESCRIPTION

FIG. 1 is a top, front and left side perspective view of a combined container and cap showing my new design;
FIG. 2 is a front elevation thereof, the rear elevation is the same except that it lacks the recess on the front of the cap;
FIG. 3 is a top plan view of the combined container and cap of the present invention;
FIG. 4 is a right side elevation, the left side is a mirror image thereto; and,
FIG. 5 is a bottom plan view of the combined container and cap of the present invention.
